REFRACTORY WALL

Robert W. Jones, Birmingham, Mich., assignor to The Bigelow-Liptak Corporation, Detroit, Mich., a corporation of Michigan

Filed Jan. 12, 1959, Ser. No. 786,340
3 Claims. (Cl. 50—418)

My invention relates to refractory walls and, in particular, to refractory walls made up of a great number of individual refractory elements that are supported upon a metal framework.

It is an object of my invention to provide a refractory wall construction which may be readily made of various thicknesses.

It is also an object of my invention to provide a refractory wall which is somewhat less expensive than conventional walls now known in the field.

My invention employs a construction in which there are three different refractory elements. One of these, a holding tile, is supported by a metal casting on the metal framework. Pairs of holding tile support a beam tile; and the combination of holding and beam tiles extend in horizontal rows which are vertically spaced from each other. In between these horizontal rows are rows of service tile which are supported by the holding and beam tile, all of which are supported by the metal castings which hold the holding tile in place.

The invention will be described in more detail in connection with a description of the accompanying drawings in which:

FIGURE 1 is a perspective view, broken away, looking at the fire face of a refractory wall constructed in accordance with my invention;

FIGURE 2 is a vertical cross section through a part of the wall of FIGURE 1;

FIGURE 3 is a horizontal view partly in section of the wall of FIGURES 1 and 2;

FIGURE 4 is a perspective view of the holding tile;

FIGURE 5 is a perspective view of the beam tile;

FIGURE 6 is a perspective view of the service tile; and

FIGURE 7 is a perspective view of a slightly modified form of wall employing the invention and one which is particularly well suited for very thin walls, such as 2" suspended walls.

The wall 1 has a fire face provided by three different types of refractory tile, viz., holding tile 3, beam tile 5, and service tile 7. All of the tile are carried by metal castings 9 upon which the holding tile 3 are mounted. The castings 9 are bolted to a steel plate or shell 11 which acts as a sink to drain heat from the C-shaped castings 9. The tile 5 and 7 are of the same thickness, as can be seen in FIGURES 2 and 3, and spread over their outside faces is a thin layer of plastic insulation 13 of a known composition acceptable in the field. Between the layer 13 and the shell 11 is block insulation 15. A vapor seal 16 may be interposed between the shell 11 and the layer 13.

Each holding tile 3 comprises a front or inside face 17 which forms a part of the fire face of wall 1. The top side of the tile 3 has adjacent the face 17 a groove 19 to receive a tongue projecting from the bottom of tile 7. A similar groove 21 is formed on the bottom side of the tile 3 to receive a tongue projecting from the top of tile 7. The top of the back portion of the tile 3 is reduced in height, as seen in FIGURE 2, and opening out of the top is a groove 23 having a rear side which is parallel to the face 17 and a front side which is tapered so as to facilitate the insertion of the tile 3 in a hanger casting 9. The bottom of the tile 3 adjacent the outer

2

or back portion has a groove 25 to receive the projections 27 on the hanger 9, the top projections 29 on the hanger 9 fitting in the top groove 23 as can be seen in FIGURE 2.

5 The beam tile 5 are supported between pairs of holding tile 3 and fit into recesses formed in the sides of the holding tile 3. These recesses comprise a section 31 that extends from the top to the bottom of the tile 3 and a section 33 which extends from the top of the tile 3 to a flat upwardly facing shoulder 35, the recess portion 31 thus being narrow along the bottom half of the tile 3 as indicated at the section 37. The ends of the beam tile 5 are shaped to fit into the recesses 31 and 33 in the ends of the holding tile 3. Thus the back half of each tile 5 is longer than the front face to provide a vertical section 31a running the full height of the tile 5 and a section 33a running a part of the height and which has a bottom face 35a to seat on the shoulder 35. The end of the tile 5 also has a narrow lower section 37a that fits in the section 37 in the end of the tile 3. The beam tile 5 has grooves 39 and 41 formed in the top and bottom, respectively, which line up with the grooves 19 and 21 in the holding tile 3 to form grooves running the length of the tile rows that receive tongues projecting from the top and bottom of the service tile 7.

10 The service tile 7 are arranged so that their length extends vertically, and the top and bottom ends have tongues 43 and 45, respectively, which project into the grooves 19 and 39 and 21 and 41 already mentioned. On one vertical side the tile 7 has a groove 47, and on the opposite vertical side it has a tongue 49 which will fit into the groove 47 on the adjacent service tile.

15 As seen in FIG. 2 substantial clearance is provided in the tongue and groove joints between the tile 3, 5, and 7, and these are filled with fairly thick layers of fire clay mortar in which the tile is set. Upon heating, the fire clay shrinks and becomes hardened and furnishes substantial space for expansion of the tile.

20 It will be noted that the hanger castings 9, by virtue of the spaced pairs of fingers 27 and 29, have a minimum area of contact with the holding tile 5 and thus a minimum contact with the hot surfaces of the wall 1. On the other hand, a very substantial area 51 on the back of the casting 9 is in engagement with the steel plate 11. Therefore, there is a small area for heat to enter the casting 9 and a large area 51 for it to be drained from the casting 9 into the plate 11, thus tending to keep the castings 9 at a relatively low temperature. The engagement of the projections 27 and 29 in the grooves 25 and 23, respectively maintains the tile 3 in a horizontal position despite the load of the other tile 5 and 7 and the load of the mortar and the plastic insulation 13.

25 FIGURES 7 to 10 show a modified form of wall 101 in which the tongue and groove type joints between the tile are modified to permit the tile to be made of less thickness than in the previous design. In the wall 101 the holding tile 103 carry beam tile 105 and the combination of tile 103 and 105 carry rows of service tile 107. The holding tile 103 are mounted on alloy casting hangers 9 which are identical to those previously described, but in this case are bolted to horizontal channels 109. The fire face of the service tile 107 are shorter than the outer faces so that there are tongues 111 projecting from the top and bottom ends of the service tile at the outer faces. These tongues 111 fit in grooves 113 in the top and bottom faces of the holding tile 103, these grooves corresponding to the grooves 19 and 21 in the tile 3. The beam tile 105 have higher fire faces than they do outside faces, thus providing grooves or cutout corners 115 to receive the projecting tongues 111 on the service tile 107. Projecting from opposite ends of the beam tile 105 and

in vertical alignment with the cutout corners 115 are tongue portions of an L-shape, each comprising a wide portion 117 and a narrow portion 119. These are received in recesses 117a and 119a which are complementary to the tongues 117 and 119 and formed by an inverted T cross section in the holding tile. There is a shoulder 121 in the tile 103 between the recesses 117a and 119a which faces upwardly and resting on it for support is the downwardly facing shoulder 123 between the projections 117 and 119 to thereby transfer load from the beam and service tile into the holding tile.

It will be apparent that the above constructions may be modified without departing from the spirit and scope of the invention.

I claim:

1. In a refractory wall structure for high temperature industrial furnaces, said wall comprising a plurality of refractory tile and C-shaped metal tile supporting brackets attached to a frame, the improvement comprising a holding tile for engagement with and support by said metal bracket, said holding tile being a block formed of refractory material and having a rectangular vertical fire face, the area of said fire face being no less than the area of any cross section through the tile parallel to said face, the vertical sides of said tile each having a groove therein consisting of a first straight portion that runs from the top to the bottom of the tile and a second straight portion that runs from the top of the tile to a plane located above the bottom of the tile so that the bottom of said second groove portion comprises an upwardly facing shoulder, grooves on the top and bottom faces of said tile running parallel to said first face and across the full width of the tile and opening into grooves on the sides of the tile, the top and bottom of said tile having additional grooves running across the full width of the tile to receive fingers on said C-shaped brackets.

2. In a refractory wall structure having an outer metal frame, a plurality of C-shaped metal castings having back faces rigidly secured against the inside surface of said frame, said metal castings being arranged in horizontal rows, holding tile fitting one within each of the C-shaped metal castings to be supported thereby and arranged in spaced relationship to each other in horizontal rows, said castings being of approximately the same width and length as the holding tile supported thereby, beam tile each supported at opposite ends upon a pair of said holding tile and arranged in the same horizontal rows as the holding tile and metal castings, and service tile arranged in horizontal rows located between the horizontal rows of beam and holding tile and supported on said beam and holding tile, the entire weight of said

service and beam tile being transferred through said holding tile to said metal castings and then into said frame, each said holding tile having a vertical cross section in the shape of an upside-down T with the width of the T being less than the width of the fire face of the tile, said beam tile having ends in the shape of upside-down L sections which fit on the T sections of the beam tile, and T and L lying on planes parallel to the fire face of the tile.

3. In a refractory wall structure having an outer metal frame, a plurality of C-shaped metal castings having back faces rigidly secured against the inside surface of said frame, said metal castings being arranged in horizontal rows, holding tile fitting one within each of the C-shaped metal castings to be supported thereby and arranged in spaced relationship to each other in horizontal rows, said castings being of approximately the same width and length as the holding tile supported thereby, beam tile each supported at opposite ends upon a pair of said holding tile and arranged in the same horizontal rows as the holding tile and metal castings, and service tile arranged in horizontal rows located between the horizontal rows of beam and holding tile and supported on said beam and holding tile, the entire weight of said service and beam tile being transferred through said holding tile to said metal castings and then into said frame, each said holding tile having L-shaped grooves in the ends thereof and each said beam tile having L-shaped projections at the ends thereof, said L-shaped projections being disposed so that the L is upside-down said L-shaped grooves and projections being disposed so that the plane of each L is transverse to the fire faces of the tile.
